(57) **CLAIM**

The ornamental design for a beach umbrella stabilizer, as
shown and described.

DESCRIPTION

FIG. 1 is a perspective view of a beach umbrella stabilizer.
FIG. 2 is a front elevational view of the beach umbrella
stabilizer.

FIG. 3 is a rear elevational view thereof.

FIG. 4 is a top plan view thereof.

FIG. 5 is a bottom plan view thereof.

FIG. 6 is a right side elevational view thereof; and,

FIG. 7 is a left side elevational view thereof.

The broken lines shown in FIGS. 1, 4, and 5 depict portions
of the beach umbrella stabilizer that form no part of the
claimed design.

1 Claim, 4 Drawing Sheets
